UNITED STATES PATENT OFFICE.

LAURENT BASSANI, OF NEUILLY-SUR-SEINE, FRANCE, ASSIGNOR, BY MESNE ASSIGNMENTS, TO BASSANI PROCESSES, INC., OF NEW YORK, N. Y., A CORPORATION OF NEW YORK.

METHOD OF AND APPARATUS FOR MAKING NEGATIVES FROM WHICH PRINTING PLATES MAY BE PRODUCED.

Application filed October 1, 1924. Serial No. 740,967.

To all whom it may concern:

Be it known that I, LAURENT BASSANI, subject of the King of Italy, residing at 4 Rue d'Armenonville, Neuilly-sur-Seine, Seine, in the Republic of France, have invented new and useful Improvements in Methods of and Apparatus for Making Negatives from Which Printing Plates May be Produced, of which the following is a specification.

My invention relates to improvements in process photography and has reference more particularly to a process of and apparatus for obtaining photographic images juxtaposed and superposed on one and the same sensitive surface during the exposure.

Transverse displacement of the cross-ruled screens used in process photography has already been applied for the purpose of shifting the pencils of light passing through the transparent spaces of the grating, so as to obtain the spreading or enlargement of the portions of the surface of the sensitive plate which are affected by the action of the pencils of light and which constitute the opaque elements of said sensitive plate, this enlargement necessarily being effected to the detriment of the transparent points of the negative, which become smaller, resulting in a reduction of the points appearing in the white spaces of the subject in the transfer upon the metal or upon a lithographic surface.

It has already been discovered that the transverse displacement of the cross-ruled screens may be successfully effected in different orientations, according to the geometric constitution of the said cross-ruled screens.

Various known devices admit of the production of the displacement under the conditions indicated. These devices in fact, permit modification of the rectilinear displacement of the screen and regulation of the amplitude of this displacement. Nevertheless, the modifications in orientation of the displacement of the cross-ruled screens have been obtained only by the operation of mechanical devices arranged in the interior of the camera. Successful operation of such devices necessitates the removal of the plate-holder, in consequence of which it is not

possible during the course of the exposure, to modify the orientation of the rectilinear displacement of the screen, since the removal of the plate-holder and locating it again would involve the risk of disturbing the precise position of the sensitive plate arranged in the holder.

The present invention has for its object to provide a process for obtaining photographic images which may be utilized in process work generally. I accomplish this object by affecting the same sensitive surface successively and partially to the action of light so as to constitute underexposed or overexposed elements which by their combination will constitute a single image obtained with different lengths of exposure, this effect being made possible by means of the suitable displacement of the screen in its own plane, a displacement which may be effected either in one or several directions. or what is more important the screen may be moved in a circular path during the exposures.

In accordance with this process it is possible to obtain monochrome reproductions of subjects in colors by using, at each of the displacements of the cross-ruled screen, color selection screens for the different colorings of the subject, so as to produce on the same sensitive surface, tone values proportional to these different colorings.

A further purpose of my invention is to provide suitable apparatus to carry out the above process, and the purpose is accomplished by means of certain arrangements and combinations of parts herein-after more fully described.

Briefly stated the present apparatus comprises a device by means of which it is possible to obtain, simultaneously with the rectilinear displacement of the cross-ruled screen in all orientation, the circular displacement of said screen about the geometric centers of the transparent elements of the grating, the modifications of amplitude and of rectilinear orientation, as well as the transformation of the rectilinear displacement into circular displacement and vice versa, all such movement being obtained instantaneously by operation of parts disposed on the outside of the camera. This

camera likewise makes it possible to control, from the outside and on an enlarged scale, the amplitude of the displacement, the camera having for this purpose a diaphragm 5 which has the shape of the elements of the screen and which is displaced over a sight of the same shape. The dimensions of the sight and of the diaphragm, as well as the amplitude of the displacement are proportional 10 to the dimensions of the transparent elements of the grating and to the amplitude of the displacement of the screen.

The invention is illustratively exemplified in the accompanying drawing, in 15 which—

Figs. 1, 2, 3, 5, and 6 are diagrams on a large scale showing the luminous locations left by the cross-ruled screen on the sensitive surface, and the effect of the displacements of said screen in certain directions.

Fig. 4 is a diagram of the reproduction camera.

Fig. 7 is the front view of the device that serves to displace the cross-ruled screen in 25 any orientation and any amplitude.

Fig. 8 is the profile view thereof.

Fig. 9 is a transverse section made along a b of Fig. 7 and broken away at the left.

My improved process consists in affecting 30 one and the same sensitive surface by means of several successive exposures: A first exposure will make it possible to obtain a plate in which the elements constituting the blacks of the subject will be formed in the usual manner, a second exposure will make 35 it possible to eliminate completely the points in the pure whites of the subject after having suitably displaced the cross-ruled screen. This second exposure will be relatively short, so as to make sure that the 40 pencils of weak light reflected by the dark tints of the original have not had time to affect the sensitive surface; it must nevertheless be sufficient to allow the pencils of 45 bright light reflected by the whites of the subject to have time themselves to affect the said sensitive surface. This action of the pencils of light will not be limited absolutely to the full whites of the subject; it 50 will manifest itself to an extent decreasing from the full whites to the light half tints, and it will have the effect of reducing the transparent points of the plate by changing 55 their form, in the direction of the displacement of the cross-ruled screen, so that the points which will express the bright tints of the subject will be deformed and will present the appearance of Fig. 1.

The constitution of points formed as in 60 Fig. 1 will tend to give the combination of the elements corresponding to the bright tints a hatched appearance, which will be the more apparent the greater a displacement of the cross-ruled screen was required by the original.

It may be desirable to obviate this hatched appearance, preserving for the points their original form, and to obtain their reduction over the entire circumference of the points formed by the original exposure. In 70 order to obtain this result, the cross-ruled screen will have to be displaced, not in a rectilinear direction as before, but circularly about geometric centers of the transparent elements of the screen, so as to obtain an action of the pencils of light over the entire circumference of the points originally established by the principal exposure. In that case the displacement of the screen will be very slight. It is necessary to observe, in fact, that the displacement of the screen will have, for the elements constituting the half tints, a different action according as it is oriented in one direction or in 75 another.

If the original exposure has established on the sensitive surface points of the form shown in Fig. 2, and if the cross-ruled screen is displaced in the direction of the arrow f to a distance l , the action of the pencil of light will manifest itself along bands of surface a , whereas if the displacement of the screen has been produced in the direction of the arrow f of Fig. 3 to the same length, the action of the pencil of light will manifest itself along two bands of surface b and c ; calculation will show that the surface of the bands of additional influence b and c (Fig. 3) is greater than the surface of the band a (Fig. 2).

The surface of additional influence obtained by the circular displacement of the screen about geometric centers of the transparent elements of the cross-ruled screen will be greater still than in the case of the preceding rectilinear displacements; but the time of exposure necessary to obtain a sufficient impression of the sensitive surface will go on increasing. At any rate, it is desirable to make it possible for the operator 105 easily to alter, in the course of the exposure, either the orientation of the rectilinear displacement of the screen or the amplitude of the circular displacement about geometric centers of the transparent elements 110 of the cross-ruled screen.

On the other hand, the displacement of the cross-ruled screen may be applied to obtaining photographic images from subjects in half tint by juxtaposition or superposition of the elements of two or more images produced on one and the same sensitive surface, after successive and partial shuttings-off of this surface, according to one method of procedure, making it possible to obtain a combined image which will be the resultant of the juxtaposed or superposed elements obtained on one and the same sensitive surface with different times of exposure.

In Fig. 4 there is seen at *s* the source of light of an elementary photographic reproduction unit, including a frame arranged to receive a negative plate 1, a board 2 supporting the objective 3, an adjustable grating-carrying frame 4 arranged to receive a cross-ruled screen 5, a frame with a curtain 6 in which there is arranged a sensitive surface 7.

If it is proposed to produce on the sensitive surface 7 a positive image of the negative 1, the cross-ruled screen 5 being removed, i. e., the process being carried on by the usual means, it will be observed that the time of exposure necessary to obtain a positive image that is complete and satisfactory in values will have to be determined with precision, and it will be observed that an underexposed plate will give more vigorous blacks, whereas an overexposed plate will give, in general, more details and less effect; the operation will thus be rendered easier and the result will be given all the desirable qualities by producing on the sensitive surface one or more images or exposures graduated within certain limits, in such manner that the elements constituting these images produce the effect of a single image uniting the qualities of the multiple images which produce it.

It would have been possible to operate differently, by producing the displacement of the cross-ruled screen in different directions and by proceeding with the use of several isolations, and to expose, for example, for 2 minutes in the original position of the screen and by causing the screen to be displaced in the direction of the arrow *f*, Fig. 6, to a distance equal to the semidiagonal of one element of the screen and by exposing the uncovered portion of the sensitive surface for 2 further minutes, the displacement of the cross-ruled screen being produced after this exposure in the direction of the arrow *f'* to a length equal to the semidiagonal of an element of the screen and the sensitive surface that is uncovered being again exposed for 2 minutes; there would thus be obtained partial and different isolations of the sensitive surface; Fig. 6 represents the combination of the elements constituting the 3 images; the elements successively isolated once, twice, or three times, i. e., for 2, 4, or 6 minutes, being represented respectively by black elements, elements with cross-hatching, and elements with simple hatching.

The movements of the cross-ruled screen that are necessary to obtain this result may be obtained by employing the mechanical device, in accordance with the invention, that is shown in Figs. 7 to 9.

There will be arranged in front of the sensitive surface a cross-ruled screen 5 of the form shown diagrammatically in Fig. 5, for

example. This screen will not be made up of two or more plates of glass suitably ruled and applied against each other, but, on the contrary, it will be constituted by a single, exceedingly plane glass, this surface being protected simply by a thin colorless varnish, the whole so that this screen may be brought into contact with, or rather to a very slight distance from, the sensitive surface 7. If the normal exposure necessary to obtain as complete as possible a positive at one time is one of four minutes, an exposure will be made, with the cross-ruled screen, for two minutes, after which the grating will be displaced in the direction of the arrow *f* (Fig. 5) to a length *m* equal to the side of one of the elements, so as to substitute the transparent elements, of the grating for the opaque elements, i. e., in such manner as to obtain the shutting off of the sensitive surface everywhere where it had originally been uncovered and to produce the exposure of this surface where it had originally been shut off. After having proceeded, under these conditions, to make a second exposure of six minutes, we shall obtain, upon development, an image made up of the juxtaposed elements of two images which have been differently isolated and which will represent, by their combination, the totality of the image.

The circular displacement of the screen about geometric centers of the transparent points of the screen, to different amplitudes, and the exposure for different periods of the portions alternately uncovered, would make it possible to obtain an image which would be the resultant of the images formed by the different displacements of the cross-ruled screen.

The transverse displacement of the cross-ruled screen in its plane would also make it possible to obtain, from subjects in colors, an image reproducing the colors of the subject by monochrome tones of proportional values. For that purpose there would be employed a panchromatic sensitive surface, and a first exposure would be made while placing in front of the objective a colored screen suitable for the selection of one color; the cross-ruled screen would then be displaced and a second exposure would be made while placing in front of the objective a colored screen suitable for the selection of another color, and so on, so as finally to obtain on the panchromatic surface the impression of the different colorings of the subject.

The screens are generally made up of elements of small dimensions; the number of elements to a centimeter is about 50 in the most usual cases, and in that case the side of one of these elements would then be $\frac{1}{5}$ of a millimeter, so that the displacement of the cross-ruled screen for the purpose of

obtaining the substitution of the opaque elements for the transparent elements, would not exceed $\frac{1}{5}$ of a millimeter.

So slight a displacement, to be obtained 5 under the required conditions, necessitates a device of great precision. It is also necessary that the regulation of the amplitude of the displacement, as well as its orientation, shall be able to be altered easily from 10 the outside of the camera, without the necessity of moving the frame holding the sensitive plate, so as to render possible the modification of the position of the screen during the exposure.

15. The device hereinafter described makes it possible to produce the displacement of the cross-ruled screen in all directions, the orientation of the displacement, as well as its amplitude, being adjustable from the outside 20 and the different positions of the cross-ruled screen in relation to its original position being controlled from the outside. It also makes it possible instantly to transform the rectilinear displacement of the 25 screen into a circular displacement about geometric centers of the transparent elements of the screen.

Referring particularly to Figures 7 to 9, 30 a grating-carrying frame 8 is displaced by rolling on balls 9 arranged at each of its corners; these balls rest against a frame 10 which guides the displacement of the frame 8 in a vertical plane and makes it possible to displace the said grating-carrying frame 35 in a direction parallel to the luminous rays either in one direction or in the other. The grating-carrying frame 8 bears attachment pieces 11 in the form of a right-angled elbow; these attachment pieces are fastened 40 to the frame 8 and arranged so as to maintain the regular distance apart of the two frames 8 and 10 and the balls 9 which permit the frame 8 to be displaced by rolling 45 on the frame 10, so that the displacement of the grating-carrying frame may be obtained in all directions and in all convenient amplitudes.

It has, besides, two plates 12 including, 50 on the one hand, two centered axles 13 which are able to rotate in the holes bored in the framework 14, and, on the other hand, spindles 15 which may be rendered eccentric and which are integral with the bearings 16, the latter being movable and adjustable in the diametral grooves of the 55 plates 12 by means of the screws 17 having milled knobs 18. Two set screws 19 are adjustable against the bearings 16 and make it possible to render the bearings 16 immovable in a determined position.

The plates 12 carry disks 20, on which divisions in degrees are marked, making it possible to regulate the orientation of the plates by bringing the suitable divisions opposite fixed pointers 21 integral with the

framework. Suitable set screws 22 which are mounted in the said framework and adjustable against the plates make it possible to render the plates 12 immovable in any position whatever.

Angular displacement or rotation of the plates 12 may be insured by a single control, which consists of two worm gears 23 keyed on the axles of the plates and engaging with two worms 24 keyed on a counter-shaft 75 25, the rotation of which is effected either by a wheel for manual operation 26, keyed to one of its ends, or by any motive element not shown.

Two systems of pantographs for the screen frame are composed of the levers 27, 28, 29, 30, 31, 32, which are assembled on the bearings 16 and on axes; these systems of pantographs are articulated about fixed axes 33 integral with the frame work 14. The grating-carrying frame 8 is attached to the axes 34 by means of yokes 35 which are attached to the frame and which carry in their forks rollers with semicylindrical grooves 36, the latter being arranged to roll 90 on the axes 34, thus making possible the horizontal displacement of the frame 8 when the guide frame 10 is displaced in the direction of the luminous rays in order to bring the grating nearer to the sensitive surface or move it further away therefrom. Adjustable screws 37 for the axes 34 have two cups into which there are placed the balls 38 which rest in the cups of the brackets 39 integral with the frame work. This arrangement is utilized for the purpose of preventing possible bending of the axes 34 under the weight of the grating-carrying frame 8; the cups merely allow very slight play in order to make it possible for the frame 8 100 to assume its very slight displacement when it is desired to displace the cross-ruled screen.

The apparatus is provided with two systems of amplifying pantographs composed of the levers 40, 41, 42, 43, 44, 45, assembled on the spindles 15 and on axes, these systems of pantographs being articulated on fixed axes 46 integral with the frame work. The levers 44 and 45 of each system of pantographs are assembled by means of an axis having a suspension pivot 47 which supports the stirrup-shaped support 51 integral with a rim 50 (Fig. 8). Owing to the stirrup-shaped support, this rim is suspended in equilibrium. Within the rim there is rotatably mounted a disk 49 which supports a diaphragm 48 of suitable shape (Fig. 7), which corresponds with that of the elements of the cross-ruled screen. Owing to the movement which the disk 49 may make in the rim 50, it will be possible to orient the openings of the diaphragm in any direction. Behind each diaphragm 48 there is arranged a graduated sight 52 (Fig. 8), which may 120 125 130

be oriented in any direction, an orientation which may be adjusted, in accordance with the pointer 53 carried by each diaphragm 48, by operation of the nuts 54 and 55 (Fig. 7), which are opposed by buffer springs, these nuts being carried by a support 56 integral with the framework of the apparatus. The sight 52 has likewise the shape of the elements of the grating.

10 The operation of the device is as follows. If we are concerned with obtaining the displacement of the cross-ruled screen, along a rectilinear orientation, it will suffice to adjust the orientation of the plates 20 by bringing the suitable divisions opposite indicating pointers 21, and then to adjust in a parallel direction the orientation of the diaphragms 48 and of the sights 52 in agreement therewith, and the displacement of the 20 cross-ruled screen will be obtained, under the conditions desired, by manual operation of the milled knobs 18. The pointers 53 of the diaphragms will indicate, on an enlarged scale, the amplitude of the displacement. 25 It is merely necessary that the graduations be made on a suitable scale. For example, if the pantographs of transmission of the movement of the spindles 15 to the grating-carrying frame 8 have been established for 30 a reduction of five times, and if the pantographs of transmission of the movement of the spindles 15 to the diaphragms 48 have been established for an amplification of five times, the amplitude of the displacement 35 of the grating will be indicated enlarged $5 \times 5 = 25$ times by the pointers 53 of the diaphragms 48 on the divisions of the sight 52.

If we are concerned with obtaining the 40 circular displacement of the grating about geometric centers of the transparent elements, it will suffice to render the spindles 15 eccentric by manual operation of the milled knobs 18 and to produce the rotation of the spindles 15 by manual operation of 45 the hand wheel 26; the amplitude of the circular displacement of the grating will be indicated, as before, on the sights 52 by the pointers 53 of the diaphragms 48.

What I claim is:

50 1. The method of making negatives from which printing plates may be produced which consists in making successive exposures of a sensitized surface part at least thereof through a screen and moving said screen in its own plane during said exposures in a path defining a closed figure.

2. The method of making negatives from which printing plates may be produced which consists in making successive exposures of a sensitized surface through a screen and moving said screen in its own plane in a circular path during said exposures.

3. The method of making negatives from which printing plates may be produced

which consists in making successive exposures of a sensitized surface at least a part of said exposures being made through a screen and moving said screen during exposure in a circular path in its own plane. 70

4. The method of making negatives from which printing plates may be produced which consists in making successive exposures of a sensitized surface through a screen and moving said screen during exposure in 75 its own plane in circular paths, the amplitude of the path of movement for each exposure differing from the amplitude of the paths of movement for the other exposures.

5. The method of making negatives from which printing plates may be produced which consists in making an exposure of a sensitized surface, thereafter making successive exposures of the same sensitive surface through a cross ruled screen and moving said screen during exposures about the geometric centers of the elements of the grating of the screen said moving being effected in the plane of the screen and at different amplitudes for each exposure. 80 85 90

6. The method of making negatives from which printing plates may be produced which consists in making successive exposures of a sensitized surface through a screen and moving said screen during exposures in 95 its own plane and in circular paths of different amplitude for each exposure, said exposures being of relatively different duration.

7. In combination, a screen and a holder 100 therefor disposed within a camera and means for moving the holder in a closed path in the plane of the screen.

8. In combination, a screen and a holder therefor disposed within a camera, and 105 means arranged outside of the camera and operatively connected with said holder for moving the latter in a circular path in the plane of said screen.

9. In combination, a screen and a holder 110 therefor disposed within a camera, means for supporting the holder, and additional means outside of the camera and operatively connected to said first means for controlling the amplitude of the displacement of the 115 holder and screen in circular paths in the plane of the screen.

10. In combination, a screen and a holder therefor disposed within a camera, means outside of said camera and operatively connected with said holder for effecting continued circular displacement of screen about the geometric centers of the transparent elements of the grating of the screen the displacement being in the plane of said screen, 120 and additional means cooperating with said first means for modifying the amplitude of displacement. 125

11. In combination, a cross ruled screen and a holder therefor disposed within a 130

camera, pantographic means disposed outside of the camera and having a part thereof projecting into the camera to support the holder, driven means for operating the pantograph comprising an adjustable spindle operatively connected to said pantographic means whereby the holder may be moved in the plane of the screen and in a circular path about the geometric centers of the transparent elements of the screen grating.

12. In combination, a cross-ruled screen and a holder therefor disposed within a camera, pantographic means pivoted within the camera and operatively connected with the holder to support the latter, the said means projecting at one end to the outside of the camera, an adjustable connection to receive the free end of said pantographic means, means for rotating said connection to cause the pantograph to orient the said holder in a path of circular movement and a control for the pantographic means or ad-

justing the amplitude of such circular path with respect to the geometric centers of the transparent elements of the screen-grating. 25

13. A pantographic control for the screen holder of a camera, comprising a system of levers, a fixed bearing therefor, means for imparting movement to said levers to cause the holder to move with the screen in circular paths in its own plane.

14. A pantographic control for the screen holder of a camera comprising a system of levers operatively connected to said holder at one end, an adjustable revolving support 35 for the opposite end of said system of levers, and a second pantographic control operatively connected to the first system and the revolving support to adjust the amplitude of circular displacement of the screen with respect to the geometric centers of the transparent elements of its screen grating.

In testimony whereof I affix my signature.
LAURENT BASSANI.
